UNITED STATES PATENT OFFICE.

DAVID N. MARKILLIE, OF BASCO, ILLINOIS.

DESIGN FOR A HOG-HOLDER.

SPECIFICATION forming part of Design No. 30,999, dated June 13, 1899.

Application filed May 13, 1899. Serial No. 716,752. Term of patent 14 years.

To all whom it may concern:

Be it known that I, DAVID N. MARKILLIE, a citizen of the United States, residing at Basco, in the county of Hancock and State of Illinois, have invented and produced a certain new and original Design for a Hog-Holder; and I do declare the following to be a full, clear, and exact description of the invention, such as will enable others skilled in the art to which it appertains to make and use the same.

The invention relates to a design for a hog-holder; and it consists in the design and configuration shown in the accompanying drawing, in which the invention is illustrated in perspective.

The leading feature of the design consists of the arched bar 1, terminating at its ends in transversely-disposed rectangular loops 2, arranged in the same plane and a plane below the highest point in the arch of the bar. 20

Having thus described the invention, what I claim is—

The design for a hog-holder, substantially as shown and described. 25

In testimony whereof I have hereunto set my hand in presence of two subscribing witnesses.

DAVID N. MARKILLIE.

Witnesses:

W. E. LYON,
S. L. McCRRORY.
